UNITED STATES PATENT OFFICE.

ROSWELL DOWNING, OF OKLAHOMA, OKLAHOMA.

LOCK FOR AUTOMOBILES.

1,408,447.

Specification of Letters Patent.

Patented Mar. 7, 1922.

Application filed January 28, 1921. Serial No. 440,563.

To all whom it may concern:

Be it known that I, ROSWELL DOWNING, a citizen of the United States, residing at Oklahoma city, in the county of Oklahoma and State of Oklahoma, have invented certain new and useful Improvements in Locks for Automobiles, of which the following is a specification, reference being had to the accompanying drawings.

10 The object of the invention is to provide a convenient and effective lock for automobiles.

Figure 1 of the accompanying drawings is a fragmental plan view of the front end 15 of an automobile on which the improved lock is in use.

Figure 2 is a similar view of a principal portion of the lock, with the upper wall of the housing broken away to expose inner 20 parts to view.

Figure 3 is an elevation view of the lock in the direction of the arrow 3 of Figure 1.

Figure 4 is a fragmental reproduction of Figure 3 on larger scale, with some of the 25 parts omitted and a portion of the rear wall of the housing broken away.

Figure 5 is a right-hand end elevation of the housing shown in Figure 4.

Figure 6 is a view in the same direction 30 as Figure 4 and on still larger scale, showing a locking-plunger.

Figure 7 is a perspective view showing an optional construction of certain parts.

Figure 8 is a fragmental reproduction of 35 the central portion of Figure 2, with certain springs omitted and with a key-controlled locking mechanism in unlocked position.

Like character of reference designate like parts in all the figures.

40 The automobile shown in this instance includes the front axle 10; the knuckles 11 which are pivoted to the ends of said axle by the vertical pivot-pins 12; the ground wheels 13 which are pivoted to the knuckles in the 45 usual manner; the side rails 14 of the framework; the supporting brackets 15 which are bolted to the front ends of said rails; and the hollow bumper-bar 16 which is supported by said brackets; these parts being in general use on automobiles.

50 In carrying out the object stated, a chain 17 is housed in each end of the bumper-bar 16 in position to be drawn out through an opening 18 in the end wall 19 of said bumper-bar and be passed through the adjacent wheel 13.

In order that the innermost end of each chain 17 shall remain positively engaged with the bumper-bar 16, said end has a short rod connection 20 attached to it, and this 60 connection is provided with an enlargement 21 which will not pass out through the opening 18.

The outer end of each chain 17 is provided with a locking terminal 22 which, after the 65 chain has been passed through the wheel 13, is inserted in an opening 24 in the rear wall 25 of the bumper-bar 16 and locked in said opening by means later described.

In further arrangement, a locking-barrel 70 26, well-known in the art of locks, is fitted revolubly in a bearing 27 at the center of the bumper-bar 16 in its front wall 28.

This locking-barrel 26 is locked against revolving movement in its bearing 27 by 75 the well known pin-and-tumbler mechanism, and may be unlocked and revolved by the usual key 29.

The inner end of the locking-barrel is provided with or formed into a crank-wheel 80 30, and locking-plungers 31 are pivoted to said crank-wheel at two diametrically opposite points.

At each of the two openings 24 the bumper-bar 16 is provided inwardly with 85 two cross-walls 32 and 33—one on each side of said opening.

Each locking-plunger 31, in extending from the crank-wheel 30, passes slidably through the first cross-wall 32 as a guiding 90 bearing and extends just to the other cross-wall 33 as best shown in Figure 4.

The cross-walls 32 may be provided with tubular extensions 34 so that the locking-plungers 31 cannot accidentally withdraw 95 from them and drop out of alinement.

As best shown in Figure 6, each locking-plunger 31 is composed of two sections 35 and 36, the section 36 telescoping the enlarged tubular end portion 37 of the section 100 35.

The tubular portion 37 of the section 35 contains a compression spring 38 which acts yieldably to force the section 36 outward and increase the length of the locking-plunger as a whole.

A pin 39 passes tightly through the section 36 and through a longitudinal slot 40 in the tubular portion 37 of the section 35; and this pin limits the lengthening movement of the sections by abutting the end of 110 said slot.

With the parts arranged in this way, the chisel-pointed tongue 23 of the terminal 22 of the chain 17 may be inserted in the opening 24 without unlocking the locking-barrel 26; said tongue forcing a shortening movement of the locking-plunger 31 and entering said opening to where the section 36 of said locking-plunger may snap to locking position through its eye 23^b under action of 10 the spring 38.

To release the locking terminals 22, the locking-plungers 31 may be withdrawn from said terminals by revolving the locking-barrel 26.

15 To draw each chain 17 back into the bumper-bar 16 when not in use, a tension spring 41 is attached to the inner end of its rod connection 20, the opposite end of said spring being extended well toward the 20 opposite end of the bumper-bar and secured to the rear wall 25 thereof by a rivet 42.

The locking terminal 22 of each chain 17 is provided with an enlargement 43 to keep from being drawn into the bumper-bar 16 25 through the opening 18; and in order that the pulling force of the springs 41 will not have to be contended with while passing the chains through the wheels 13 for locking, the rod connection 20 of each chain is 30 provided with a slight enlargement 44, this enlargement acting to prevent the pull of the springs when the neck portion 45 of said connection is slipped into the notch 46 in the edge of the opening 18.

35 The bumper-bar 16 is provided with a central opening 47 in its rear wall 25, to allow access to inner parts, and this opening is closed by a flanged cover 48.

This cover 48 is held in place by two rivets 40 49 which pass through it and forward through the front wall 28 of the bumper-bar 16; the heads of these rivets being counter-sunk enough so that they cannot be readily removed by portable tools.

As shown in Figure 7, a section of cable 45 50 may be substituted for each chain 17.

A cushion spring 51 of bar spring steel may be carried in front of and spaced from the bumper-bar 16, the ends of this spring being curved rearward and inward as at 52 50 and secured to the ends of the bumper-bar by bolts 53.

An additional bow spring 54 may be secured to the center of the rear face of the spring 51 by rivets 55, the free ends 56 of 55 this spring 54 bearing against the front face of the bumper-bar 16.

This arrangement of the springs 51 and 60 54 provides a suitable cushion in case of collision and keeps the bumper-bar from being bent or having its contained parts thrown out of working alignment.

Having thus described the invention, what I claim and desire to secure by Letters Patent is:—

In an automobile lock, a hollow bumper-bar having an outlet opening, a flexible member extending through said outlet opening, yieldable means within the bumper-bar acting to draw the flexible member in through 70 said outlet opening, a limiting stop carried by the inner end of the flexible member to keep it from being drawn completely out through the outlet opening, a second stop carried by the outer end of the flexible member 75 to keep it from being drawn completely in through said opening, and a third stop carried by the flexible member between the two first-named stops, the outlet opening having a notch at its edge adapted to receive that portion of the flexible member between the first-named stop and the third stop and thereby prevent the flexible member from being drawn into the bumper-bar.

Witness my hand this 15th day of January, 1921.

ROSWELL DOWNING.
